UNITED STATES PATENT OFFICE.

ALLAN A. ADAMSON, OF ROCHESTER, NEW YORK, ASSIGNEE TO GEORGE H. HARRIS,
OF ROCHESTER, NEW YORK.

CIGAR BOX.

Application filed January 31, 1925. Serial No. ~~xxxx~~

The present invention relates to cigar boxes and more particularly to the edging and labeling thereof. An object of the invention is to provide for edging and labeling a cigar box so that the edging and labeling may take place on automatic machinery with a minimum number of operations. A further object of the invention is to provide a single blank which will produce substantially all of the edging for the box body and having included therein one or more labels usually applied by separate operations. A further object of the invention is to provide an edging which may be quickly applied to the box body and will leave at the same time an exposed surface of the box at the upper portion of the rear wall for the attachment of a cover or lid hinging strip directly to such surface.

20 To these and other ends, the invention consists of certain parts and combinations of parts, all of which will be hereinafter described: the novel features being pointed out in the appended claims.

25 In the drawings:

Fig. 1 is a perspective view of a box constructed in accordance with this invention, the lid or cover being partially broken away;

30 Fig. 2 is a plan view of a blank employed for edging and labeling the front and end walls and portions of the rear wall;

Fig. 3 is a plan view of a blank employed for edging and labeling the cover;

35 Fig. 4 is a rear view of the cover after its edging and labeling blank is secured thereto;

Fig. 5 is a rear view of the box after the cover or lid has been applied;

40 Fig. 6 is a detail plan view of an edging piece employed for edging the rear edge of the cover and the upper rear edge of the rear wall.

Fig. 7 is a plan view of another embodiment of the invention in which the blank is made from a number of separate strips united together before being applied to the box.

Referring more particularly to the drawings, 1 indicates the bottom of the box, 2 the end wall, 3 the front wall, and 4 the rear wall, the end walls projecting above the front and rear walls as is common in cigar boxes. The blank illustrated in Fig. 2 is applied to the body of the box, whereas the

blank illustrated in Fig. 3 is applied to the cover 5 of the box.

In Fig. 4 is shown the top face of the cover after the combined label and edging blank has been applied thereto, this blank embodying a label and edging portion 6 having tongues 7 at opposite edges foldable on the lines 8 and 9 to cover opposite side edges of the cover or lid and to extend on the top surface of such cover or lid. This blank also has a tongue which is foldable on the lines 11 and 12 to cover the free or swinging edge of the box and to extend on the top surface. At the rear edge of the cover a label forming tongue 13 is connected to the blank 6 to fold on the lines 14 and 15, this label forming tongue being secured to the inner face of the rear wall and containing any suitable advertising matter as will be the main or body portion of the blank.

The blank for edging the body comprises four sections 17, 18, 19 and 20. The sections 18 and 20 edge the ends of the box and the sections 17 and 19 edge, respectively, the front wall and portions of the rear wall of the box. The sections 17, 18, 19 and 20 are foldable on the lines 21, 22, and 23, and the section 17 has at its end a section 24 foldable on the line 25 and adapted to be covered by the section 20. The section 17 has at its lower edging a tongue 26 foldable on the line 27 to extend over the bottom of the box and a tongue 28 foldable on the lines 29 and 30 to cover the upper edge of the box. The tongue 28 is shorter than the tongue 26 and beyond its ends the section 17 has extensions or tongues 31 which are of lengths sufficient to extend upon those portions of the end walls 2 which project above the front and rear walls. The section 18 has a tongue 32 at its lower edge for extending onto the bottom 1 and a tongue 33 at its upper edge to extend over the upper edge of the end wall, being foldable upon lines 34 and 35, and down on the inner face of such end wall. This tongue also has shoulders 36 which are located from the fold line 34 at a distance equal to the difference between the upper edges of the end walls and the upper edges of the front and rear walls.

This section 18 also acts as a label for containing suitable advertising matter. The section 18 is wider than the section 17 and the fold line 35 is coincident with the extensions 31 of the section 17.

The section 19 is recessed or cut away at 37 at its top in order to leave exposed the upper edge of the rear wall for attachment of a cover hinging strip 16. On opposite 6 sides of this cut away portion the section 19 has short extensions 38 projecting to the fold line 35 of the end sections to edge the end walls above the rear walls. The bottom of this section 19 has a tongue 39 which 10 is foldable on the line 39^a to edge the underside of the bottom 1. The other end section 20 is constructed in this instance identically like the end section 18 and a detail description thereof is unnecessary.

15 In applying the blank shown in Fig. 2 to the box body the blank is first wrapped entirely about the body and then the tongues on the upper and lower edges of the section are folded inwardly to cooperate with the 20 upper edges of the box and the bottom of the box. The cover is wrapped with the blank shown in Fig. 3 and when completed its top surface will appear as shown in Fig. 4. The cover is then applied to the edged 25 box body so that the rear of the box at this stage will appear as shown in Fig. 5. Then a short strip 40 is applied to cover the hinge and, at the same time, edging the rear top surface of the cover and the rear 30 upper surface of the rear wall, this edging piece being folded on the line 41.

In the embodiment shown in Fig. 7, the blank is made from a number of pieces of strip material adhesively secured together 35 to provide the four sections. In this instance, two longitudinally extending strips 42 and 43 are provided with transverse strips 44, 45, 46 and 47 connecting the longitudinal strips, the upper strips being shorter 40 than the lower strip and extending throughout three sections, while the lower strip extends throughout four sections so as to provide an open top section which will permit the cover to be directed to the rear 45 wall of the box. The strip 42 provides edging for the top and two end walls of the box. The strip 43 provides edges for the lower part of all of the walls of the box. The strips 44 and 47 provide edging for 50 the rear corners of the box and the strips 45 and 46 provide edging for the two front corners of the box. Notches 48 may be provided in the strip 43 at the cross strips 44, 45, 46 and 47, while notches 49 may be provided in the upper strip 42 at the cross strips 44 and 47, inclusive, so that tongues are provided between the notches for covering the bottom wall of the box in one instance and the upper edge of the box in the 55 other instance except for the rear wall. After this blank has been fitted to the box the cover is applied thereto and then a blank such as shown in Fig. 6 is applied to the rear edge of the cover and the upper

edge of the box as in the other embodiment 65 of the invention.

From the foregoing it will be seen that there has been provided a means for edging and labeling cigar boxes through which the 70 number of operations is reduced to a minimum. The edging means for the box body is substantially all contained in one blank which preferably also contains some of the 75 box labels. This blank embodies in it a number of sections and when folded provides edging for all four vertical walls, as well as the bottom wall. In this instance, the blank sections are four in number arranged end to end and each adapted 80 for attachment to one of the vertical walls, having also provision for extending upon the bottom wall and also for edging the upper edges of the vertical walls, except that provision is made in the blank for exposing 85 the upper edge of the rear wall so that the hinge of the cover may be attached directly to the material of which the box is made and this hinge as well as the rear top surface of the lid or cover is edged by a 90 separate piece applied after the cover is fitted thereto.

What I claim as my invention and desire to secure by Letters Patent is:

1. A cigar box comprising a box body, a 95 cover, a hinging strip secured to the outer face of the rear wall of the box body and to the top face of the rear edge of the cover, an edging blank covering the lower edge of the rear wall, the rear edge of the bottom wall and the opposite side edges of the rear wall and cut away to expose the upper edge 100 of the rear face of the rear wall of the box for the attachment of the hinging strip after the application of the edging blank, and a separate edging blank for covering 105 the hinging strip and edging the outer face of the upper portion of the rear wall of the box and the top face of the cover in proximity to the rear edge of the latter.

2. In combination with a box having a 110 hinged cover and a hinging piece adhesively secured to the rear edge of the cover and the upper edge of the rear wall of the box, an edging blank embodying four sections 115 arranged end to end and each coextensive in length with one of the vertical walls of the box, said sections, each having a tongue located on one and the same side of the blank extending over the bottom of the box, three of said sections having tongues extending over the upper edges of the front wall and the end walls of the box and the other of said sections being recessed to leave exposed the outer face of the upper edge of 120 the rear wall of the box and a separate 125 edging piece covering the hinging strip.

3. In combination with a box body a cover, a hinging strip secured to the outer

face of the rear wall of the box body and to the top face of the rear edge of the cover, a single blank having incorporated therein a plurality of sections including edging for 5 the four vertical corners, the four lower horizontal corners and the side and front top edges of three of the vertical walls of the box, said blank having a cut away portion exposing the upper edge of the outer 10 face of the rear wall for attachment of a cover hinging strip directly to such wall and a separate blank covering the hinging strip and edging the upper portion of the rear wall of the box body and the rear edge 15 of the cover.

4. A cigar box having a hinged cover, an

edging blank secured thereto and embodying four sections arranged end to end and in one piece of material, said sections each having a tongue located on one and the same side of the blank and extending over the bottom of the box, three of said sections having tongues extending over the upper edges of the front wall and end walls of the box and the other of said sections being 20 recessed to expose the outer face of the rear wall of the box, and a separate edging blank edging the upper portion of the rear wall of the box and the top face in proximity to the rear edge of the latter. 25
